UNITED STATES PATENT OFFICE.

JOHN WHITE, OF EDINBURGH, SCOTLAND.

SEPARATOR FOR PAPER-PULP.

1,333,287.

Specification of Letters Patent.

Patented Mar. 9, 1920.

Application filed March 22, 1919. Serial No. 284,439.

To all whom it may concern:

Be it known that I, JOHN WHITE, a subject of the King of the United Kingdom of Great Britain and Ireland, and residing at 5 Edinburgh, Scotland, have invented a certain new and useful Improvement in Separators for Paper-Pulp, of which the following is a specification.

This invention has for its object to provide a separator for paper pulp which will effectually open up or separate the bunches of fibers, so that the fibers may more easily part with any undesirable matter that may adhere to them before they reach the strainer 15 or wire of the paper making machine.

The invention is illustrated in the accompanying drawing in which Figures 1 and 2 are sections at right angles to one another showing a construction including a liquid 20 spraying device, Fig. 1 being a section on the line *a*—*b*, Fig. 2.

As shown, the separator comprises a vat or chest 1 in which the separating operation takes place, said vat being divided into 25 compartments 2 by substantially vertical or inclined fixed or upstanding and depending partitions or sluices 3 and 3', respectively, the direction of flow of the pulp being alternately downward and upward, 30 whereby the lighter undesirable matters may be retained at the upper level of the vat by upstanding partitions 3, while the heavier undesirable matters settle by gravitation and may pass into a chamber or chambers 4 35 below the vat.

Preferably a transparent plate 6 is fitted at the most convenient position to permit the

accumulation of refuse matters to be observed.

There is incorporated in the separator a 40 scouring device comprising a water spray pipe 19 the jets issuing from each of which impinge against the upper edge of the adjacent partition 3, such edge being beveled and serrated.

What I claim is:—

1. A separator for paper pulp comprising a vat, upstanding and depending partitions dividing said vat into compartments, said partitions so arranged that the path of 50 pulp flowing through said vat is alternately downward and upward, said upstanding partitions formed with beveled edges and means for directing jets of fluid on to the pulp passing over said edges. 55

2. A separator for paper pulp comprising a vat, upstanding and depending partitions dividing said vat into compartments, said partitions so arranged that the path of 60 pulp flowing through said vat is alternately downward and upward, whereby lighter undesirable matters are retained by the upper 65 edge of an upstanding partition at the upper level of the vat and heavier undesirable matters are brought to the bottom of said vat, and a transparent inspection plate adjacent to the bottom of said vat.

In testimony whereof I have signed my name to this specification in the presence of two subscribing witnesses.

JOHN WHITE.
